UNITED STATES PATENT OFFICE.

ABEL G. STILSON, OF COBLESKILL, NEW YORK.

FLOOR-TUBE.

SPECIFICATION forming part of Letters Patent No. 317,684, dated May 12, 1885.

Application filed May 10, 1884. (No model.)

To all whom it may concern:

Be it known that I, ABEL G. STILSON, of Cobleskill, in the county of Schoharie and State of New York, have invented certain new 5 and useful Improvements in Floor-Tubes, of which the following is a specification.

This invention has reference to an improved safety wall or floor tube for stove-pipes that can be adjusted to any thickness of floors or 10 partitions through which a stove-pipe is to be passed; and the invention consists of a safety-tube that is composed of two telescoping sections, each having an inwardly-projecting and perforated guard-ring and an exterior seat at 15 one end, said sections being connected by adjustable straps and loops to the thickness of the partition-wall or floor.

In the accompanying drawings, Figure 1 represents a vertical central section of my im- 20 proved safety-tube for stove-pipes. Fig. 2 is a horizontal section of the same on line x x , Fig. 1. Figs. 3 and 4 are detail views of the fastening device of the safety-tube.

Similar letters of reference indicate corre- 25 sponding parts.

A in the drawings represents a stove-pipe which is surrounded by a safety-tube, B, at the point where the stove-pipe passes through a floor or partition-wall. The safety-tube B con- 30 sists of two telescoping sections, C' and C², by which the length of the tube B can be adjusted to the thickness of the floor or partition. Each section C' and C² is provided at its outer 35 edge with an exterior flange, e, that rests against the wall or floor, and with an inwardly-projecting guard-ring, f, the inner diameter of

which corresponds to the size of the stove-pipe. The guard-rings f have perforations f' f'' to admit the circulation of the air in the annular space between the stove-pipe A and the safety-tube B. The telescoping sections C' and C² are connected by straps D D of sheet metal or wire, which are secured at one end respectively to the upper or lower section, C' or C², of the tube B, and connected at their inner overlapping 40 ends by loops d d, of sheet-metal or wire, around which the inner ends of the straps D D are bent when the sections C' C² have been adjusted to the thickness of the wall or floor, as shown in Figs. 1 and 3.

By keeping different sizes of safety-tubes corresponding to the sizes of stove-pipes in stock they can be put up without difficulty, either by the tinsmith or by any one putting up a stove.

Having thus described my invention, I claim as new and desire to secure by Letters Patent—

A wall and floor tube for stove-pipes, con- 55 sisting of two telescoping sections, C' and C², provided with exterior flanges, e, inwardly-projecting guard-rings f, having perforations f', and connecting-straps D D and loops d d, substantially as described.

In testimony that I claim the foregoing as 60 my invention I have signed my name in presence of two subscribing witnesses.

ABEL G. STILSON.
